UNITED STATES PATENT OFFICE.

GARRETT T. SMITH, OF CHICAGO, ILLINOIS, ASSIGNOR TO SAUERMAN BROS., INC., OF CHICAGO, ILLINOIS, A CORPORATION OF ILLINOIS.

MATERIAL-MOVING APPARATUS.

Application filed February 23, 1926. Serial No. 89,879.

- My invention relates to improvements in material moving apparatus of the type disclosed in U. S. Letters Patent No. 1,159,803, granted November 9, 1915, to H. B. Sauer-
5 man, and involving, generally stated, an inclined cable way along which a carriage is movable, the carriage being provided with a bucket, or the like, supported thereon with its center of gravity, when loaded, extending in the rear of its point of support, the carriage being further provided with a pivoted rearward extension engaged by a flexible element, as for example, a chain which is connected with one end of the bucket and
10 at its other end carries a block which runs along the cable and, adjacent the point of dumping, engages a stop for effecting the swinging of the bucket to dumping position, against the action of gravity.
15 20 Apparatus of the type above referred to as hitherto provided, presents the objection that the pivoted rearward extension of the carriage, in the continued downward movement of the latter, after the block engages the stop, when the parts of the apparatus are so proportioned as to produce the best practical results, sometimes drops and strikes the bucket with the manifest disadvantage.
25 30 One of my objects is to provide improvements to the end that the pivoted extension referred to may not drop sufficiently far to strike the bucket; another object is to provide cushioning means effective in the operation of dumping the bucket, to reduce shock, and minimize wear; another object is to provide for the accomplishment of both of the above first-referred-to objects by a single mechanism, and other objects as will be
35 40 manifest from the following description.
- Referring to the accompanying drawings:—
- Figure 1 is a view in elevation of an apparatus constructed in accordance with my invention, the apparatus being shown in the position it assumes after the bucket has been loaded and is travelling downwardly on the cable way to the point of dumping. Figure 2 is a top plan view of the apparatus illustrated in Fig. 1 with the bucket omitted, this view being taken at the line 2 on Fig. 1 and viewed in the direction of the arrow; and Figure 3, a view like Fig. 1 showing the bucket in dumped position.
45 50 55 The inclined cable way which would be supported, in practice, to extend across the material to be moved as, for example, the ground to be excavated or dredged, is represented at 4 and, in accordance with common practice, is so associated with other parts, not shown, as to permit it to be slackened for permitting the bucket to be engaged with the material to be used, and drawn to taut condition preparatory to the operation of transferring the bucket to the point of dumping.
60 65 70 75 Mounted on the cable 4 to travel thereon is a carriage 5 which, in the construction illustrated, is formed of a pair of frames 6 secured together in spaced relation by connectors certain of which are shown at 7 and 8 and support rotating pulleys 11 at which the carriage is supported on the cable way 4 to be adapted to be moved along the latter.
75 80 85 90 95 The dumping scraper or bucket represented at 12 is of a form generally used, its forward open digging end being provided with a cutting-edge portion 13. According to the arrangement illustrated in the drawings, the bucket 12 is supported from the carriage 5 in such a manner that when loaded the center of gravity of the bucket will be toward the rear of the latter, the bucket in this construction being supported from the carriage by means of a cable 14 which is connected at one end with an eye 15 on the rear end of the bucket 12, and with a bail 16 connected with the forward end of the bucket, this bail being provided with a row of openings certain of which are shown at 16^a at any one of which the clevis portion 14^a of the cable may connect. The cable 14 intermediate its ends runs over a pulley 17 journaled on the carriage 5 between the frame members 6 thereof.
100 105 110 The hauling line, through the medium of which the carriage and bucket are moved along the cable way, is represented at 18 and terminates in sections 19 and 20, the section 20 being connected, as indicated at 20^a, with the forward end of the bucket 12, and the section 19 passing over a pulley 21, journaled on a pin 21 on the frame 5 and connecting at one end with the bail 16, at a clevis 19^a thereon.
The bucket 12 is also connected at 22 with one end of a cable 23 which passes over a pulley 24 journaled on the carriage 5, and

thence around a pulley 25 journaled on an arm 26 pivotally connected at 27 to the carriage 5 and extending rearwardly therefrom in a direction lengthwise of the cable

- 8 4, the end of the cable 23 adjacent the pulley 25 being provided with a block 28 which straddles the cable 4 and is movable along the latter, the block 28 being provided with a pulley 29 which engages the cable 4 to reduce friction. The block 28 is provided for cooperation, in a manner hereinafter described, with a stop device 30 adapted to be clamped to the cable 4 at any desired point along the latter and positioned on this cable 15 below the block 28.

The arm 26 is provided with a link 31 pivotally connected, at its lower end with the arm 26, as indicated at 32, the upper end of this link carrying a roller 33 journaled thereon and bearing against the upper surface of the cable 4.

- 20 In the operation of the apparatus described, the line 4 is first slackened to allow the bucket 12 to engage with the material to be moved, whereupon the hauling line 18 is drawn on, causing the bucket to fill. The operator then causes the cable 4 to become more or less taut as conditions render it desirable, thus lifting the bucket 12 away from the material on the ground and permitting it and the carriage to move down the cable way 4 under the control of the operator paying out the hauling line 18. When the carriage moves down on the cable 4 to a position in which the block 28 engages the stop 30, the block 28 is arrested in its downward move along the cable 4 and continued movement of the carriage downwardly along the cable way will thus cause the bucket to be moved to the dumping position represented in Fig. 3, the cable 14 in this operation running over the pulley 17. As the center of gravity of the bucket is toward the rear end thereof the movement for rolling the bucket 45 into dumping position is against gravity and is strictly under the control of the operator handling the hauling line 18, and thus the roll-over movement may be a gradual, or a rapid, one as desired.
- 50 The function of the link 31 is two-fold. One function performed by it is to prevent the arm 26 from swinging downwardly and striking the bucket 12 in the movement of the carriage 5 downwardly on the cable way 4 after the block 28 has engaged the stop 30. In this connection it may be stated that whereas there is no need of a link, such as link 31, to hold the extension 26 in raised position when the block 28 is out of engagement with the stop 30 as shown in Fig. 1, due to the fact that the block 28 extends adjacent the outer end of this arm, there is need of such a link when the arm 26 moves downwardly relative to the block 28, as in such movement the leverage exerted on the

arm 26 tending to hold it up, becomes less and less, and of such small amount, when the parts of the apparatus reach dumping position, that the arm 26 when made of the most practical length, will not be held up by the cable 23 alone and oftentimes strikes the bucket. The link 31 thus operates as a check, permitting of the use of as long an arm 26 as is desired, without possibility of this arm striking the bucket.

The second function above referred to, of the link 31, is that of cushioning the carriage and bucket in the downward movement of the same to dumping position to the end that the impact of these parts against the stop 30 will be absorbed. This function is produced by the link 31 engaging the block 28 in the final movement of the parts of the apparatus. In the continued descent of the carriage along the cable way 4, after the block 28 has engaged the stop 30, the arm 26 swings downwardly to a position in which it is supported by the link 31 from the cable way 4, the link in this position of the parts extending at substantially a right angle to the arm 26. Near the end of the downward movement of the carriage, the link 31 strikes the block 28 with the result of moving the link 31 and the arm 26 to the position shown in Fig. 3, the engagement of the link with the block as stated serving to exert a force against the arm 26 tending to swing it upwardly at its pivot 27. It will be noted that as the link 31 swings about its pivot 32, the angular distance between the cable way 4 and the arm 26, is reduced, against the resistance of the arm 26, due to its weight, and the amount of this resistance is very rapidly increased as the angular distance referred to is decreased, thus resulting in the arresting of the movement of these moving parts within a comparatively short distance and with minimum shock.

It will be understood that by adjusting the stop 30 along the cable way 4, the dumping of the bucket may be effected at any desired point on the cable.

It will furthermore be understood from the foregoing description and the drawings, that following the dumping of the bucket, the same may be readily righted by pulling on the hauling cable 18.

By providing the multiplicity of holes 16^a in the bail 16 of the bucket the connections of the cables 14 and 19 with the bucket may be made at the desired points for properly balancing the loads when composed of varying materials and under varying conditions of operation.

While I have illustrated and described a particular construction in which my invention is embodied, I do not wish to be understood as intending to limit it thereto, as the same may be variously modified and altered,

and the invention embodied in other forms of structure, without departing from the spirit of my invention. Furthermore, I do not wish to be understood as intending to limit my invention to an apparatus wherein a slack line is employed with a bucket of the type shown operating thereon, as it may be embodied in an apparatus employing a cable cooperating with a bucket in the form 10 of a so-called skip which would be loaded at one elevation, as by dumping the material into it, and then allowed to descend on the line to the point of dumping at which it would be automatically dumped, as explained 15 of the construction shown.

What I claim as new, and desire to secure by Letters Patent, is:

1. In apparatus of the character set forth, the combination of an inclined cable, a carriage movable thereon and provided with a rearwardly projecting extension pivoted to the body of the carriage, a bucket supported 20 on said carriage with the center of gravity of the bucket, when loaded, in the rear of its point of support, a hauling line for the bucket, a block running on said cable, a cable, or chain, connected with said block and with said bucket to the rear of its center of gravity and movable on said carriage and 25 extension, a stop on said inclined cable adapted to be engaged by said block upon the descent of the bucket on said inclined cable, and means engaging said extension for preventing downward swinging of said 30 extension against said bucket.

2. In apparatus of the character set forth, the combination of an inclined cable, a carriage movable thereon and provided with a rearwardly projecting extension pivoted to the body of the carriage, a bucket supported 40 on said carriage with the center of gravity of the bucket when loaded, in the rear of its point of support, a hauling line for the bucket, a block running on said cable, a cable, or chain, connected with said block and with said bucket to the rear of its center of gravity and movable on said carriage and 45 extension, a stop on said inclined cable adapted to be engaged by said block upon the descent of the bucket on said inclined cable, and means engaging said extension and said first-named cable for limiting 50 downward swinging of said extension.

3. In apparatus of the character set forth, the combination of an inclined cable, a carriage movable thereon and provided with a rearwardly projecting extension pivoted to the body of the carriage, a bucket supported 55 on said carriage with the center of gravity of the bucket, when loaded, in the rear of its point of support, a hauling line for the bucket, a block running on said cable, a cable, or chain, connected with said block and with said bucket to the rear of its center of gravity and movable on said carriage 60 and 65 center of gravity and movable on said car-

riage and extension, a stop on said inclined cable adapted to be engaged by said block upon the descent of the bucket on said inclined cable, and a member connected with said extension and overlying said first- 70 named cable for limiting downward movement of said extension, the connection between said member and extension adapting these two last referred to elements for relative movement. 75

4. In apparatus of the character set forth, the combination of an inclined cable, a carriage movable thereon and provided with a rearwardly projecting extension pivoted to the body of the carriage, a bucket supported 80 on said carriage with the center of gravity of the bucket, when loaded, in the rear of its point of support, a hauling line for the bucket, a block running on said cable, a cable, or chain, connected with said block 85 and with said bucket to the rear of its center of gravity and movable on said carriage and extension, a stop on said inclined cable adapted to be engaged by said block upon the descent of the bucket on said inclined 90 cable, and a link pivoted on said extension and overlying said first-named cable for limiting downward movement of said extension. 95

5. In apparatus of the character set forth, the combination of an inclined cable, a carriage movable thereon and provided with a rearwardly projecting extension pivoted to the body of the carriage, a bucket supported 100 on said carriage with the center of gravity of the bucket, when loaded, in the rear of its point of support, a hauling line for the bucket, a block running on said cable, a cable, or chain, connected with said block and with said bucket to the rear of its center of 105 gravity and movable on said carriage and extension, a stop on said inclined cable adapted to be engaged by said block upon the descent of the bucket on said inclined cable, and a member connected with said extension and overlying said first-named cable and into the path of downward movement of which said block, when engaging 110 said stop, extends, the connection between said member and extension adapting these two last-referred-to elements for relative movement. 115

6. In apparatus of the character set forth, the combination of an inclined cable, a carriage movable thereon and provided with a rearwardly projecting extension pivoted to the body of the carriage, a bucket supported 120 on said carriage with the center of gravity of the bucket, when loaded, in the rear of its point of support, a hauling line for the bucket, a block running on said cable, a cable, or chain, connected with said block and with said bucket to the rear of its center of gravity and movable on said carriage 125 and extension, a stop on said inclined cable 130

adapted to be engaged by said block upon the descent of the bucket on said inclined cable, and a link pivoted on said extension and overlying said first-named cable and into the path of downward movement of which said block, when engaging said stop, extends.

7. In apparatus of the character set forth, the combination of an inclined cable, a carriage movable thereon and provided with a rearwardly projecting extension pivoted to the body of the carriage, a bucket supported on said carriage with the center of gravity of the bucket, when loaded, in the rear of its point of support, a hauling line for the bucket, a block running on said cable, a cable, or chain, connected with said block and with said bucket to the rear of its center of gravity and movable on said carriage and extension, a stop on said inclined cable adapted to be engaged by said block upon the descent of the bucket on said inclined cable, and means operating automatically to exert a force on said extension in a direction to lift it against its tendency to swing downwardly, in the movement of said extension along said first-named cable after said block engages said stop.

8. In apparatus of the character set forth, the combination of an inclined cable, a carriage movable thereon and provided with a rearwardly projecting extension pivoted to the body of the carriage, a bucket supported on said carriage with the center of gravity of the bucket, when loaded, in the rear of its point of support, a hauling line for the bucket, a block running on said cable, a cable, or chain, connected with said block and with said bucket to the rear of its center of gravity and movable on said carriage and extension, a stop on said inclined cable adapted to be engaged by said block upon the descent of the bucket on said inclined cable, and a link pivotally connected with said extension and having a portion at which it overlies said first-named cable, said link being located between the point at which said extension is pivotally supported on said carriage and the point at which said second-referred-to cable engages said extension, said link operating to limit the downward swinging of said extension and being so positioned that it engages with said block for swinging said extension upwardly, following the engagement of said block with said stop.

GARRETT T. SMITH.
